[57] CLAIM

The ornamental design for a gaming cabinet, as shown and described.

DESCRIPTION

FIG. 1 is a front perspective view of a gaming cabinet, showing my new design;

FIG. 2 is a front elevational view of the gaming cabinet illustrated in FIG. 1;

FIG. 3 is a right elevation view of the gaming cabinet illustrated in FIG. 1.

FIG. 4 is a left elevational view of the gaming cabinet illustrated in FIG. 1;

FIG. 5 is a top plan view of the gaming cabinet illustrated in FIG. 1;

FIG. 6 is a bottom plan view of the gaming cabinet illustrated in FIG. 1; and,

FIG. 7 is a rear elevational view of the gaming cabinet illustrated in FIG. 1.

The broken line showing in FIGS. 1 and 2 is for illustrative purposes only, and forms no part of the claimed design.
